(57) **CLAIM**

The ornamental design for a millwork sanding sponge, as shown and described.

DESCRIPTION

FIG. 1 is a view in perspective of a millwork sanding sponge;

FIG. 2 is an end elevation view thereof;

FIG. 3 is a top plan view thereof;

FIG. 4 is a bottom plan view thereof;

FIG. 5 is a right side elevation view thereof; and,

FIG. 6 is a left side elevation view thereof.

UNITED STATES PATENT AND TRADEMARK OFFICE
CERTIFICATE OF CORRECTION

PATENT NO. : Des. 527,974 S
APPLICATION NO. : 29/219539
DATED : September 12, 2006
INVENTOR(S) : John G. Petersen

Page 1 of 1

It is certified that error appears in the above-identified patent and that said Letters Patent is hereby corrected as shown below:

Col. 1, Line 5: "Vamer" should be shown as -- Varner --

Signed and Sealed this

Twentieth Day of March, 2007

A handwritten signature in black ink, appearing to read "Jon W. Dudas". The signature is written in a cursive style with a large, stylized "J" and "W".

JON W. DUDAS
Director of the United States Patent and Trademark Office
